(57) **CLAIM**

The ornamental design for a pivot fan base, as shown and described.

DESCRIPTION

FIG. 1 is a top front perspective view of a new design for a pivot fan base;

FIG. 2 is a front elevation view thereof;

FIG. 3 is an enlarged right elevation view thereof with the fan rotated ninety degrees;

FIG. 4 is a greatly enlarged top plan view thereof;

FIG. 5 is a greatly enlarged bottom plan view thereof;

FIG. 6 is an enlarged left elevation view thereof with the fan rotated ninety degrees; and,

FIG. 7 is an enlarged rear perspective view thereof.

The broken line showing of a fan grill, a handle, decorative members on the fan hub, fan blades, and the fan motor is included for the purpose of illustrating environmental structure and forms no part of the claimed design.
